DISPLAY CASE AND MOUNTING THEREFOR

Anthony A. Rose, Oakland, Calif., assignor to
M. J. Frick Hamilton, Los Angeles, Calif.

Application November 5, 1932. Serial No. 641,409

10 Claims. (Cl. 312—114)

The invention relates to glass display cases and mountings therefor, and particularly to the type arranged for positioning on a counter.

An object of the invention is to provide a device of the character described in which the case may be supported in a manner permitting the adjustable positioning thereof for extension over or from the counter to any degree desired.

Another object of the invention is to provide a display case of the character described, having mounting means which permits stacking of the cases one upon the other and serves to securely lock the cases together in stacked relation.

A further object of the invention is to provide mounting means for the cases which may serve to support the case in adjustable position on the counter or to secure the cases together in stacked relation.

The invention possesses other objects and features of advantage, some of which, with the foregoing, will be set forth in the following description of the preferred form of the invention which is illustrated in the drawing accompanying and forming part of the specification. It is to be understood, however, that variations in the showing made by the said drawing and description may be adopted within the scope of the invention as set forth in the claims.

Referring to said drawing:

80 Figure 1 is a vertical sectional view of an end portion of a case and mounting designed in accordance with my invention.

Figure 2 is a vertical sectional view, on a smaller scale, of the device taken at right angles to Figure 1.

Figure 3 is a perspective view, on a still smaller scale, of the complete case and mounting.

Figures 4 and 5 are perspective views of the inner and outer end-frames of the case.

40 Figures 6 and 7 are perspective views of modified forms of the mounting brackets.

As illustrated in the drawing the device of my invention includes a display case unit 2 here shown as what is commonly termed a double decker and formed of sections 3 and 4 arranged in stacked or superposed relation. Each section is provided with end frames 5 designed to support glass plates 6 and 7 forming the top and bottom 50 of the case, and a glass plate 9 defining the front wall of the case. The plates 6 and 7 rest on flanges 12 and 13 respectively, at the top and bottom of the frames. However when the sections are used in multiple, as in the present embodiment, one of said plates such as the top of the

bottom section, or as is here shown the bottom plate 7 of the upper section, is omitted.

Novel means are provided for securing together the adjacent frames of the different sections, so that as many sections as desired may be readily stacked one upon the other and firmly locked together. Formed on the upper and lower sides of each frame are complementary portions 15 and 16 suitable for obtaining a dove-tail connection.

In the present instance the male portion of such connection is provided at the bottom of the sections while the female portion is provided at the top of the sections. It will thus be clear that the sections may be readily secured together by sliding the male portion of one frame into the female portion of the adjoining frame of the other section. The portions 15 and 16 preferably extend for the full length of the frames, so that when the dove-tail portions are completely engaged the frames of the connected sections will be effectively secured together.

As a means of locking the connected frames together as well as retaining the glass plates in proper position in the section, an outer frame 19 is provided for use with the inner frame 5. The outer frame is designed to fit over both of the connected inner frames and is formed at the top and sides with side and end flanges 21 and 22

united along one edge and arranged to respectively fit against the side and end faces of the frames. The side flange, while present at the top of the frame, is omitted at the bottom so that the male portion of the under section is left free.

It will now be evident that after the inner frames are connected and the plates properly positioned therein, it is merely necessary to slip the outer frame over inner ones, and the parts will be positively held and locked in operative assembly. The outer frame is preferably secured in position by means of screws 23 passing through apertures 24 and 25 in the outer and inner frames respectively.

To retain the inner frames of a given section together, a connection rod 26 is secured to such frames. It is to be noted that the outer frame not only serves as a means of retaining the frames and plates together, but to completely enclose and conceal such frames as well as the end portions of the plates. Preferably a glass plate 27 is supported at the outer end of each inner frame, and such plates are arranged to be held in position in the vertical flanges 22 of the outer frame. It will now be clear that the assembly of the case is a very simple matter, and should it be desired to effect a change in the number of sections comprising the unit, practically the only

change required is a substitution of the outer end-frames.

If desired, a glass closure plate 28 may be provided at the rear side of each section. As here shown each of such plates is fitted in a casing 29 having hinge pivots 31 which rotatably fit in bearings formed by associated journal portions 32 and 33 provided in the outer and inner frames respectively.

10 A most important feature of the invention is the mounting means for the case whereby the latter may be supported on a counter or the like and its position varied with respect to the counter without disturbing the connection between the case and counter or requiring a substitution of the mounting means. In the present embodiment the mounting means aforesaid is of such design that it utilizes as a part thereof the means on the inner frames for securing the frames together.

20 As will be clear from Figures 1 to 3, the cases is arranged to be secured to a counter A or the like by means of a pair of brackets 34. The latter which form a support are of a design which will support the case in spaced relation to the counter and in such manner as to leave the top surface of the counter practically unobstructed. The bottom end of each bracket is preferably in the form of a clamp 36 which fits over the edge of the counter and is anchored in place by a set screw

30 37. The upper end of each bracket is formed with a female dove-tail portion 38 which is arranged for the reception of and slidable engagement with any one of the male portions provided on the bottom of the inner frames. It will now be clear that to mount the case on the brackets, it is merely necessary to enter the portions 16 of the lower frame into the portions 38 of the brackets and then slide said last portions through the grooves until an effective interlock between

40 the relatively slidable parts is secured. As will also be readily understood, with the parts thus interlocked any desired position of the case with respect to the counter may be readily attained by the mere expediency of sliding the case one way or the other upon the brackets. Thus if it is

45 desired to have the case extend well over or toward the front of the counter as indicated by the dash lines in Figure 2, the case should be slid well forwardly, and on the other hand should it be desired to have the case in a relatively retracted position it should be drawn backward as indicated by dotted lines in said figure. When the case is positioned in the desired relation, the parts may be locked by means of a set screw 39 so as to prevent any accidental shifting of the case. Preferably a stop 41 is provided on the outer frame so as to prevent undue forward extension of the case over the bracket.

50 If it is desired to support the case in close relation to the counter or the like, brackets such as shown in Figures 6 and 7 may be used, the bracket 42 in the Figure 6 being arranged for positioning entirely upon the upper surface of the counter, whereas the bracket 43 in Figure 7 is formed with a clamp for engagement with an edge of the counter as in the instance shown in Figure 1.

55 It will now be clear that the device of my invention is well adapted to the accomplishment of the objects hereinbefore referred to.

70 I claim:

1. In a device of the character described, a plurality of display case sections each including a set of walls and end frames for carrying said walls, a support for a section, cooperating portions on the frames and support for holding them

interlocked and adjustable the former on the latter, a portion on each of said frames independent of said first portion thereon arranged for cooperation with said cooperating portion of one of the other frames to interlock said sections together, and an outer frame positioned over connected frames of adjacent sections to lock the frames together. 80

2. In a device of the character described, a display case section including a set of transparent walls and a pair of end frames for carrying the walls, a support therefor, cooperating portions on the bottom of each of said frames and on the top of said support for interlocking the frames with the support and adjustably positioning the former on the latter, a portion on the top of each of said frames corresponding to the said portion on the support, and an outer frame covering the top and sides of each of the first frames. 85

3. In a device of the character described, a plurality of display case sections each including a set of walls and inner frames receiving the ends of said walls, supporting brackets, cooperating portions on the bottoms of the frames and on the tops of said brackets for holding them interlocked and slidable in the frames on the brackets, a portion on the top of each of said frames corresponding to the portion on the bracket whereby the frames of the different sections may be interlocked, an outer frame positioned over the sides and top of the inner frames to retain the interlocked frames against relative sliding movement and to cover the ends of said walls, and means to limit the sliding movement of the frames with respect to the brackets. 95 100

4. A display case for a counter including a set of walls, end frames for carrying said walls, supporting members mounted on said counter and having a lateral extension for slidably supporting said end frames for movement rearwardly of or forwardly over said counter, and adjustable locking means carried by said members and engaging said frames for locking said frames against relative movement on said members at positions intermediate the forward and rearward positions of the frames. 110 115

5. A display case for a counter including a set of walls, end frames carrying said walls, and supporting brackets mounted at the rear of said counter and each having a laterally extending portion slidably engaged by the bottom of an end frame, said bracket portions being substantially smaller than said frame bottoms whereby upon movement of the end frames either rearwardly of or forwardly over the counter the bracket portions will at all times be substantially completely under and covered by said end frames and indisposed for interfering with the service on the part of the waiter at the rear of the counter or with the patron at the forward portion 120 125 130 135 of the counter.

6. A display case comprising a plurality of sections each including a set of walls and end frames having lateral extensions carrying said walls, engageable portions on said end frames 140 interlocking the same one over the other in slidable engagement with each other, supporting members for said sections, engageable portions on said members and lower end frames interlocking the same in slidable engagement, said member portions being substantially shorter than the engaging frame portions whereby relative adjustment between said frames and members is afforded while maintaining said member portions under and substantially completely cov- 145 150

- ered by said engaging frame portions, and means depending from said lower end frames for engaging and stopping relative movement of said member portions.

5 7. A display case comprising a plurality of sections each including a set of walls and end frames carrying said walls, engageable portions on said end frames interlocking the same one over the other in slideable engagement with each other, supporting members for said sections, engageable portions on said members and lower end frames interlocking the same in slideable engagement, and outer frames fitting around said end frames and locking the same together and terminating 10 short of and leaving exposed for engagement 15 said lower frame portions.

8. A display case comprising a set of walls and end frames carrying said walls, outer casings around said end frames, opposed outstanding and 20 covering portions on said frames and casings defining a pair of bearings, and a pair of projections carried by one of said walls engaging in said bearings and pivotally supporting the wall for movement to and from a case closing 25 position.

9. In a device of the character described, a display case, a support therefor, said support having lateral extensions and cooperating portions on the extensions and case for adjustably, slidably positioning the case on the support, means for mounting said support on a base, said mounting means and said cooperating portions for said case and support being constructed to prevent tilting of said display case during all positions of adjustment.

10. In a device of the character described, a display case, a support therefor, said support having transversely extending portions and cooperating portions on the case and the transversely extending portions for adjustably, slidably positioning the case on the support, means for mounting said support on a base, said mounting means and said cooperating portions for said case and support being constructed to prevent tilting of said display case during all positions of adjustment.
